UNITED STATES PATENT OFFICE.

CHARLES B. HITCHCOCK, OF INDIANAPOLIS, INDIANA.

CIGAR-LIGHTER CUTTER.

SPECIFICATION forming part of Letters Patent No. 269,934, dated January 2, 1883.

Application filed February 10, 1882. (No model.)

To all whom it may concern:

Be it known that I, CHARLES B. HITCHCOCK, a citizen of the United States, residing at Indianapolis, in the county of Marion and State of Indiana, have invented certain new and useful improvements in a device or machine for making thin shavings of wood for cigar-lighters, of which the following is the specification.

10 My invention relates to a machine for utilizing cigar-boxes and cutting them into thin shavings for the purpose of using them as cigar-lighters, in which a knife is fastened into a metal-casting and projects from one side, the top of which is in the same plane or line as the rear guiding-flange, and in front of the knife is a flange for the purpose of guiding the parts of the cigar-box to be cut, which, after passing over the knife, is guided by the rear flange.

15 The side holding the knife is adjustable vertically and gages the thickness of the shaving to be cut, while the cigar-box cover or other part of the box is guided and held steady during its passage over the knife.

20 In the accompanying drawings, Figure 1 is a perspective view, showing the cutter with a cigar-box cover, H, or bottom, in position to be operated upon. Fig. 2 is a view of the adjustable side plate with the knife attached. Fig. 3 shows the base with its horizontal guiding and vertical flanges. Fig. 4 is a cross-section through the line of the knife, showing the clamping-screw a. Fig. 5 shows a portion of the adjustable side with the adjusting-screw and knife in position.

25 Similar letters refer to like parts throughout the various views.

A represents the base, with its horizontal projecting flange F and vertical guide C.

30 B is the adjustable side, having the knife K fastened through near its middle and projecting from one side, with the adjusting-screw S.

The base A has projecting flanges b below, which serve as a support to steady it upon the table, and upon which, also, the adjusting-screw rests. A flange, o, projects from the front end, which serves as the bottom guide to the knife. This flange is depressed under the knife, and serves to guide and steady the shaving

while it is being cut. The upper part of the 50 base serves as a vertical guide for the cigar-box cover or bottom while it is being moved over the knife K.

The side B is adjustable upon the base A by means of the slotted holes p and the adjusting-screw S' S".

A projecting flange, F', is placed in the rear of the knife K and upon the same plane as the top of the knife. It is designed to have the flanges F and F' in different planes, and only 60 to the thickness of the shaving between these planes. By this method the cigar-box lid is held steady and makes a shaving of equal thickness, which makes an excellent cigar-lighter.

65 The knife is a plain flat piece and fastened by a set-screw, a, near one end, as shown by section in Fig. 4.

What I claim as my invention, and desire to secure by Letters Patent, is—

70 1. In a machine for making cigar-lighters, a base-plate having a vertical side integral therewith recessed near the middle to admit a cutting-blade, and provided with a flange to form a portion of the support for the block 75 to be shaved, in combination with an adjustable side plate having an opening near the middle to receive a cutting-blade, and provided with a flange to form another portion of the support for the block to be shaved, a 80 cutting-blade, top bolts for holding the same in place, and means for uniting the parts, substantially as described.

2. In a machine for shaving cigar-lighters, the base-plate A, having the recessed vertical side 85 C integral therewith, and the flange F, in combination with recessed side plate, B, provided with the supplementary flange F', the knife K, set-screw a, and means for uniting the parts into one machine, substantially as described. 90

In testimony whereof I have signed my name to this specification in the presence of two subscribing witnesses.

C. B. HITCHCOCK.
